BLOWPIPE

Wilgot J. Jacobsson, Elizabeth, N. J., assignor, by
mesne assignments, to Union Carbide and Car-
bon Corporation, a corporation of New York

Application November 9, 1934, Serial No. 752,205

15 Claims. (Cl. 158—27.4)

This invention relates to the control of the fluid flow through one of a plurality of passages leading from a common source and has important application to blowpipes and particularly to oxy-gas blowpipes for use in cutting by means of a preheating flame and an oxygen jet wherein the cutting oxygen and that for supporting combustion of the preheating gas are supplied from a common source through divergent 5 branches of a common inlet passage.

In blowpipes of this character the fuel gas for use in preheating the work is supplied from a source through a fuel gas passage, and the oxygen for supporting combustion of the pre- 15 heating fuel gas and that for cutting are supplied from a common source through branch passages or conduits leading from a common chamber or main passage. Flow of oxygen from the main passage to supply the cutting jet is through a passage under control of a valve 20 located between the connection of the preheating oxygen passage with the main passage and the tip of the blowpipe. Opening of this valve tends to rob the branch leading to the fuel gas passage of oxygen causing the pressure therein 25 to drop. When the valve is again closed, this pressure is restored and as a consequence the quantitative flow of oxygen from the source to the mixing chamber varies with the opening and closing of this valve. Should the valves 30 controlling the supply of oxygen and fuel gas to the mixing chamber be originally set for a neutral mixture with the control valve for the cutting oxygen passage closed, opening of this latter valve will cause the preheating flame to 35 become carbonizing. If the preheating flame is originally adjusted to neutral with the cutting oxygen control valve open, upon closing this valve, the flame will become oxidizing. Neither 40 of these conditions is desirable in cutting operations since excess carbon robs the flame of heat, thereby slowing the cutting operation, while a strongly oxidizing flame has relatively poor flashback resistance.

Ordinarily, in cutting metals, a high velocity 45 cutting jet is required while in such work as flame machining, desseaming, and the like a low velocity jet is utilized. Separate special blowpipes have generally been required for these different classes of work, and in some instances a 50 metering plug may be inserted in the head of a single combination blowpipe for throttling down the cutting oxygen passage so as to adapt a high velocity blowpipe for low velocity work. 55 This latter arrangement, while better than the

previous practice, is unsatisfactory because an interchange of plugs is impracticable without first cooling the blowpipe head. Furthermore, alternate heating and cooling tends to loosen the plugs in their seat in the head and renders 5 them insecure and undependable.

One object of this invention is to provide improved means whereby the flow of fluid in one of a plurality of passages branching from a common source may be maintained quantitatively 10 constant regardless of variations in the fluid flow through another of the branch passages.

A further object of the invention is to provide in a single blowpipe improved means adapting the blowpipe for both high and low velocity cutting jobs and in which interchangeable metering plugs used to this end are not subjected to 15 the heat of the blowpipe flame.

Other objects and novel features of the invention will become apparent from the following description taken with the accompanying drawing illustrating one embodiment of the invention and in which:

Fig. 1 is a longitudinal section through the handle of a cutting blowpipe showing a construction and arrangements of parts in accordance 25 with this invention;

Fig. 2 is an elevation of the head of the blowpipe on a reduced scale;

Figs. 3 and 4 are cross sectional views respectively on lines 3—3 and 4—4 of Fig. 1;

Fig. 5 is a fragmentary longitudinal sectional view on line 5—5, Fig. 4, showing the construction arrangement of the metering plug in the cutting oxygen passage of the blowpipe;

Fig. 6 is a detail sectional view on line 6—6 of Fig. 1 of the booster nozzle on an enlarged scale compared with Figs. 1 and 5, showing the construction of the passage therethrough at its discharge end.

The invention is illustrated in the accompanying drawing as applied to a cutting blowpipe although it is clearly applicable to any analogous device or situation in which it is desired to maintain the flow of fluid, through one of a plurality of conduits branching from a common source, quantitatively constant regardless of variations in flow that may occur in other of the branch conduits.

The blowpipe, as illustrated, comprises a head N of usual construction which is connected with a handle H by means of a cutting oxygen pipe O^c and a pipe C for a preheating mixture. The handle H is comprised of a front body or block

10 and a rear body or valve block 11 connected by a tubular casing 12.

The front body is bored to provide passages 13 and 14 with the forward ends of which, pipes 5 O^c and C respectively connect. The rear body is also bored to provide a main oxygen passage or chamber O and a fuel gas passage F, the latter under control of throttle valve 16. Passages O and F are respectively adapted for connection 10 with sources of oxygen and fuel supply through nipples 17 and 18. The main oxygen passage O is connected with passage 13 in the front body by means of a conduit 19 and passage F is connected with the passage 14 by a conduit 20 which respectively form continuations of passages O and F. Passage O is also connected with the passage 14 by means of a cross passage provided by a conduit 21 which may be provided with a flashback resisting coil 22 located within the casing 20 12 so as to contact with the walls thereof and thereby provide maximum bore for accommodation of pipes 19 and 20 and other mechanical accessories, to afford a bracing of the casing walls and afford maximum length of the flashback resisting coil. The passage through conduit 21 is partly formed in the rear body by suitably boring this body and preferably has a portion 21^a coaxial with and connected to the forward end of the main oxygen passage O. Flow of 30 oxygen through conduit 21 is under control of a throttle valve 24.

Conduit 19 is connected with the forward end of the main oxygen passage O by a portion 19a thereof extending radially of the latter passage. Flow of cutting oxygen to the head N through pipe O^c is under control of an operator through valve V located in a valve chamber 25 formed in the front block 10 by counterboring the passage 13. This valve is normally held closed against 40 a nozzle-like seat 26 by a spring 27 and operates within the bore of a plug 28 in which the seat 26 is located. The plug 28 is threaded into the valve chamber 25 and the rear end of this chamber is closed by a plug 29 having a bore 30 therethrough to slidably accommodate the stem 31 of the valve V. The plug 29 is spaced from 28 sufficiently to provide an inlet chamber 25^a constituting a part of valve chamber 25. A leak preventing packing 32 is provided at the rear end 50 of the plug 29 around stem 31 and is held in place by a gland nut 33. The stem 31 may be conveniently formed in two parts 31^a and 31^b adjustably connected at 34 for varying the length thereof. Stem 31 is extended through the coil 55 22 and is slidably supported at its rear end in a bearing 31^c formed on the rear body or block 11.

The valve V is under control of suitable means operating upon the stem 31, as a valve-opening lever L of the second class having an arm 35 extending lengthwise of the handle and an arm 36 extending diametrically thereof through a slot 37 in casing 12 and pivoted at 36^a to the rear body. The major portion of arm 36 is therefore enclosed within the casing for purposes of protection thereof and compactness of the apparatus. Lever arm 36 is provided with an opening into which is threaded a set screw 36^b for adjustably limiting movement of arm 36. The lever arm 35 is provided at its free end with a slot 38 through which the shank 39 connecting a latch 40 to a thumb button 41 extends. The latch 40 is adapted to be extended through a slot 42 in the casing 12 for latching the lever arm 35 in depressed position and valve V open. When 70 the outside arm 35 of the L-shaped lever is de-

pressed, the stem 31 will be engaged by a portion of the arm 36 between the pivot 36^a and the arm 35, thus pushing the stem 31 forwardly to unseat the valve V.

A mixing chamber M is also provided in the front block 10 by counterboring passage 14. The mixing chamber M is constructed with a shoulder 43 between which and ring screws 44 threaded thereinto is held a mixing nozzle 45 having an axial bore 46 of constricted cross section at its 10 discharge end.

The nozzle 45 is provided intermediate its length with an annular groove 47 constituting a distributing chamber into which the fuel gas conduit 20 discharges. The rear end of the mixing chamber is closed by a plug 48 threaded thereinto and spaced from the ring screws 44 so as to provide an inlet chamber 49 into which oxygen conduit 21 discharges.

In order to overcome the disadvantages hereinbefore set forth, a baffle member 50 is arranged within the main oxygen passage O to serve as a preheating oxygen booster operating to maintain the flow of oxygen through conduit 21 quantitatively substantially constant under conditions of 25 an increase in velocity of the gas flowing through passage O, when the cutting oxygen control valve V is either opened or closed. This baffle member is threaded into a counterbore 21^a of conduit 21, is located at the forward end of passage O and is 30 coaxial with this passage and the portion 21^a of conduit 21; the construction being such that the baffle member 50 will discharge through portion 21^a into conduit 21. The baffle member 50 is provided with an axial bore 51 terminating at 35 its discharge end in a portion 52 internally hexed or otherwise conveniently shaped to accommodate a suitable tool for securing the baffle in the counterbore or removing it therefrom. The baffle member 50 extends the major portion of the 40 length of chamber or passage O and is spaced from the wall thereof to provide an annular chamber 53 which surrounds the nozzle and communicates with conduit 19. The baffle 50 thus serves as a baffle separating the flow of oxygen in passage O into two parts which are delivered to conduits 19 and 21, respectively. 45

In operation, the preheating oxygen normally flows continuously through conduit 21 but, when the cutting oxygen valve V is opened, the velocity of the oxygen in passage O increases with an accompanying decrease in pressure and would, except for the baffle member 50, decrease quantitatively the flow of preheating oxygen through conduit 21 to the mixing chamber M. By providing the baffle 50 and by its peculiar construction and arrangement in passage O as described herein, the increase in velocity of the oxygen due to the sudden inrush of oxygen through passage O, when valve V is opened, causes an increase in the rate of flow into the passage of conduit 21 so that opening of valve V has negligible influence on the quantitative flow of oxygen into the passage of conduit 21.

In order to adapt the blowpipe to various work conditions, as in changing from high velocity cutting operations to deseaming or low velocity rivet cutting, I have provided a plurality of metering screw plugs 54 of various lengths to be suitably placed interchangeably in the apparatus to varyingly restrict the cutting oxygen passage. These screws may be placed at any point in the cutting oxygen passage but I preferably place them so as to project from the rear end of the rear body 11 into the cutting oxygen passage at the junc- 75

ture between conduit 19 and the portion 19^a thereof. In this position the screw plugs are not likely to become overheated and thereby loosened and, so located, may be removed and replaced at 5 any time without necessity of first allowing the blowpipe to cool.

Variations in the construction and arrangement of parts herein described may obviously be made within the broad scope of the invention and the 10 invention is not to be restricted to blowpipes or to any particular type of blowpipe but is applicable in whole or in part to various situations where it is desired to maintain the flow of fluid through one of a number of conduits branching from a 15 common source of supply quantitatively constant regardless of variations in the flow through another of the branches or in the common source.

I claim:

1. A blowpipe having a fuel gas inlet conduit 20 and an oxygen inlet conduit, said oxygen inlet conduit having its inner end enlarged; branch passages communicating with the enlarged end of said oxygen inlet conduit, one of said branch passages delivering preheating oxygen to be 25 mixed with fuel gas and the other branch passage delivering cutting oxygen; said preheating oxygen passage having a removable wall extending into the enlarged end of said oxygen inlet conduit to maintain substantially constant the 30 flow of preheating oxygen regardless of variations in the flow of cutting oxygen.

2. In a blowpipe, a member having fluid passages therethrough; a removable tubular baffle member comprising the inlet end of one of said 35 fluid passages extending into another of said fluid passages and providing communication between said passages; the said baffle member having an unconstricted passage therethrough for maintaining the flow of fluid from one of the 40 passages to the other quantitatively constant regardless of changes of velocity in the passage from which the gas flows.

3. A member having a fluid inlet passage therein and passages branching from one end thereof; 45 means for throttling the flow of fluid through one of the branch passages; and a tubular baffle having its inlet in the first-named fluid passage and having an unconstricted bore and having an outlet opening into the other of said branch passages 50 and so constructed and arranged as to maintain the flow of fluid through said other branch passage quantitatively constant regardless of variations in flow in the throttled branch passage.

4. In a blowpipe, the combination of a body 55 comprising a tubular handle and blocks secured to and closing the front and rear ends of said handle; a valve in the front block; a stem entirely within said handle for operating said valve and slidably supported by both of said blocks; 60 means carried by the rear block for actuating said stem to operate said valve; a fuel gas inlet conduit and an oxidizing gas inlet conduit, both within the rear block; and conduits extending through said handle and severally communicating with said inlet conduits; one of said communicating conduits within said handle comprising a coiled portion having adjacent coils in close proximity to each other; said stem and a portion of the other of said communicating conduits being 65 surrounded by said coiled portion.

5. In a blowpipe, the combination of a tubular handle; a fuel gas inlet conduit and an oxidizing gas inlet conduit, both adjacent one end of said handle; conduits extending through said handle 70 and severally communicating with said inlet con-

duits, one of said conduits within said handle comprising a coil and another of said conduits within said handle extending through said coil; a valve controlling the flow of gas through one of the conduits within said handle; and means for operating said valve comprising a stem extending through said coil and projecting beyond the opposite ends of the latter. 5

6. A blowpipe having a fuel gas conduit and an oxygen supply conduit, said latter conduit terminating at the exit end thereof in one end of an enlarged chamber; a cutting oxygen conduit communicating with said chamber at a side thereof; and a preheating oxygen conduit for delivering oxygen to be mixed with the fuel gas, said 10 preheating oxygen conduit extending into said chamber to a point beyond the entrance to said cutting oxygen conduit, and having an inlet portion communicating with said chamber at a point opposite the exit end of the supply conduit. 15

7. A blowpipe as claimed in claim 6, in which said preheating oxygen conduit is unconstricted and is of smaller diameter than said oxygen supply conduit. 20

8. A blowpipe as claimed in claim 6, in which the inlet portion of said preheating oxygen conduit extending within said chamber is of smaller diameter than said oxygen supply conduit and is in substantially axial alignment with the exit end thereof. 25

9. A blowpipe as claimed in claim 6, in which the outer surface of the inlet end of said extended inlet portion of the preheating oxygen conduit is tapered so as to reduce turbulence in the oxygen flowing to the cutting oxygen conduit. 30

10. A blowpipe as claimed in claim 6, in which the said extended inlet portion of the preheating oxygen conduit is removably secured in an end wall of said chamber. 35

11. A blowpipe comprising, in combination, a 40 tubular handle; a front block secured to and closing one end of said handle; a rear block secured to and closing the other end of said handle; a fuel gas conduit and an oxidizing gas conduit, both disposed within said handle; a valve in one 45 of said blocks controlling the flow of gas through one of said conduits; and means for operating said valve comprising a valve stem slidably supported adjacent its ends by said blocks for longitudinal movement within said handle, one of said gas conduits having a coiled portion surrounding a part of the other of said gas conduits between the ends of the latter and also surrounding a part of said valve stem between the ends of the latter. 50

12. A blowpipe comprising, in combination, a 55 tubular handle; a front block secured to and closing one end of said handle; a rear block secured to and closing the other end of said handle; a fuel gas conduit and an oxidizing gas conduit, both conduits being disposed within said handle; a valve carried by one of said blocks and controlling the flow of gas through one of said conduits; means for operating said valve including a valve stem supported by said blocks for longitudinal movement within said handle, and an L-shaped lever having one arm thereof pivoted on the other of said blocks within said handle and adapted to actuate said valve stem, the other arm of said lever being disposed outside of and extending along said handle; one of said gas conduits having a coiled portion surrounding a portion of the other of said gas conduits and a portion of said valve stem. 60

13. A blowpipe comprising, in combination, a 65

tubular handle; a front block secured to and closing one end of said handle; a rear block secured to and closing the other end of said handle; a fuel gas conduit and two oxidizing gas conduits within said handle; a valve carried by one of said blocks and controlling the flow of gas through one of said oxidizing gas conduits; and means for operating said valve including a valve stem within said handle and slidably supported by both of said blocks for movement longitudinally of said handle; the other of said oxidizing gas conduits comprising a coiled portion surrounding a portion of said fuel gas conduit, a portion of said valve stem and a portion of the oxidizing gas conduit controlled by said valve.

14. A blowpipe comprising, in combination, a tubular handle; a front block secured to and closing one end of said handle; a rear block secured to and closing the other end of said handle; a fuel gas conduit within said handle; two oxidizing gas conduits within said handle; a valve carried by said front block and controlling the flow of gas through one of said oxidizing gas conduits; and means for operating said valve including an L-shaped lever having arms of unequal length, the shorter lever arm extending into said handle and pivoted adjacent its end on the rear block, and a valve stem within said handle and slidably supported adjacent its ends by said blocks for movement longitudinally of said handle, a portion of said shorter arm between such pivot and the longer lever arm being adapted to engage an end of said valve stem and actuate the latter to

unseat said valve, said longer lever arm being disposed outside of said handle and extending longitudinally of the latter from adjacent said rear block toward said front block, whereby the free forward end of said longer arm is readily operable by a finger of a hand holding said blowpipe.

15. A blowpipe comprising, in combination, a tubular handle; a front block secured to and closing one end of said handle; a rear block secured to and closing the other end of said handle; a fuel gas conduit within said handle; two oxidizing gas conduits within said handle; a valve carried by one of said blocks and controlling the flow of gas through one of said oxidizing gas conduits; and means for operating said valve including an L-shaped lever having arms of unequal length, the shorter lever arm extending into said handle and pivoted adjacent its end on the other of said blocks, and a valve stem within said handle and having its ends slidably supported by said blocks for movement longitudinally of said handle, a portion of said shorter arm between such pivot and the longer lever arm being adapted to engage and actuate said valve stem to unseat said valve, said longer lever arm being disposed outside of said handle and extending longitudinally thereof, the other of said oxidizing gas conduits comprising a coiled portion within said handle and surrounding a portion of said fuel gas conduit, a portion of said valve stem, and a portion of the oxidizing gas conduit controlled by said valve.

WILGOT J. JACOBSSON.
